UNITED STATES PATENT OFFICE.

HARRY M. PFLAGER, OF ST. LOUIS, MISSOURI, ASSIGNOR TO CAST STEEL PILOT COMPANY, OF ST. LOUIS, MISSOURI, A CORPORATION OF DELAWARE.

PILOT.

Application filed May 28, 1923. Serial No. 641,989.

To all whom it may concern:

Be it known that I, HARRY M. PFLAGER, a citizen of the United States, residing at St. Louis, Missouri, have invented a certain new 5 and useful Improvement in Pilots, of which the following is a full, clear, and exact description, such as will enable others skilled in the art to which it appertains to make and use the same, reference being had to the accompanying drawings, forming part of this 10 application.

My invention relates to railroad rolling stock and consists in an improved pilot mounting adapted to be used on locomotives, 15 electric cars, self-propelled gas cars, or other railroad vehicles on which a pilot may be provided.

The objects of my invention are to facilitate application and removal of the pilot 20 to and from the pilot beam or like frame member; to render the pilot easily movable to and from its normal operating position; to permit removal of a truck mounted near 25 the pilot; and to provide for adjustment of the pilot to different heights to compensate for wear of wheels, journal bearings or settling of the spring rigging or other changes in the condition of the vehicle which cause 30 a lowering of the pilot and brings the same too close to the rails or roadway.

In the accompanying drawings which illustrate a selected embodiment of my invention as applied to a railroad locomotive,—

Figure 1 is a side elevation of my pilot 35 applied to a pilot beam and indicating the front wheel of the locomotive to which the pilot is attached and the track upon which it runs. This figure also shows the pilot moved to an inoperative position.

Figure 2 is a front elevation of the structure 40 shown in Figure 1.

Figure 3 illustrates a pilot beam differing slightly from that shown in Figures 1 and 2.

It will be understood that the locomotive 45 frame is mounted upon several wheeled trucks, the front one of which is indicated at 1 and shown as traveling upon the rail 2 of a trackway. The front of the locomotive frame includes a pilot beam 3 extending 50 across the front of the locomotive and preferably, but not necessarily, formed of a one-piece casting provided with forwardly projecting lugs 4 arranged in pairs at intervals along the middle portion of the beam. The 55 pilot 5 may be of any desired type, shape,

and construction, and is here shown as formed of a one-piece casting provided with upwardly projecting members 6 upon its rear face located at intervals so that they may be inserted in between adjacent lugs 4 60 upon the pilot beam. Lugs 4 and projections 6 each form knuckle elements of a hinge construction for mounting the pilot upon the pilot beam. This hinge construction is completed by the bolts 7 which serve 65 as pintles and are secured in place by ordinary nuts, cotters or other retaining elements.

I have shown lugs 4 as provided with apertures 8 arranged above the apertures 70 which receive the pintle bolts 7 and these apertures are provided for the purpose of enabling the pilot to be mounted at a different height from that shown. If, as suggested above, the spring rigging settles so 75 as to reduce the distance from the pilot to the rail below the minimum allowed, the bolts 7 may be removed and the pilot raised far enough to permit the insertion of the bolts 7 through apertures 8. 80

The pilot is braced in its normal operating position by means of brackets 9 which are bolted to the pilot at 10 and to the lower face of the beam at 11. Additional bolt 85 openings 13 are provided in the pilot to accommodate bolts 10 when the pilot is raised as described above.

With my construction, the removal of bolts 11 through the beam and brackets 9 will enable the pilot to be swung to the 90 dotted line position indicated in Figure 1 or thereabouts which will permit the front truck of the locomotive to be removed with a minimum of labor. When the pilot beam is again returned to its normal operative position it is only necessary to attach bolts 11 to complete the operation. Heretofore it has been customary to attach the pilot to the front end of the locomotive by means of numerous bolts and nuts passing in different 100 directions through the pilot beam, and it has been customary to use washers and liners to make the parts register properly. In order to remove the front truck it was necessary to remove all these bolts and nuts, lift the pilot out of position and after the truck was replaced to replace the pilot in position, apply all of the bolts and nuts, washers and shims, which is not always done 105 rightly, so that the parts after being replaced 110

may not be in good operating condition. These disadvantages are eliminated by my improved construction. It will be understood that my invention may be embodied in built-up beams and pilots as well as in the unitary castings illustrated.

In Figure 3 I show a pilot beam in which the bracket 14, corresponding to one of the brackets 9 in Figures 1 and 2, is formed integrally with the beam. This construction may be preferable where the brackets are spaced apart far enough to permit the truck to be moved between them.

Other modifications in the details of construction may be made without departing from the spirit of my invention as set forth in the accompanying claims.

I claim:

1. In a railroad vehicle, a frame, supporting wheels, and a pilot pivotally mounted thereon so as to be swung vertically as a unit out of the horizontal plane of said wheels.
2. In a railroad vehicle, a frame, a pilot pivotally mounted thereon, and means for adjusting vertically the pivotal mounting of the pilot.
3. In a railroad vehicle, a frame, a pilot pivotally mounted thereon, and means for adjusting the pivotal mounting of the pilot to vary the height of its operative position.
4. In a railroad vehicle, a frame, a pilot pivotally mounted thereon, at the upper portion of the pilot so that it may be swung upwardly away from the vehicle support.
5. In a railroad vehicle, a frame, a pilot hinged at spaced points along its upper extremity to the end portion of the frame so as to swing in a vertical plane, and means for securing the pilot in operative position.
6. In a railroad vehicle, a wheeled truck, a frame supported thereby, a pilot so mounted

on said frame adjacent to said truck that it may be swung upwardly and away from the latter to facilitate removal of the truck.

7. In a railroad vehicle, an underframe including a pilot beam, a pilot hinged to the front thereof and movable forwardly and upwardly about its hinge, and a detachable connection between said beam and a part of said pilot spaced from its hinged point.

8. In a railroad vehicle, an underframe including a pilot beam having forwardly projecting elements forming hinge knuckles, a pilot having upwardly projecting elements forming cooperating hinge knuckles, removable pintles for connecting said knuckles, and a bracket for bracing said pilot from said beam and detachably secured to the latter.

9. In a railroad vehicle, an underframe including a pilot beam having forwardly projecting elements forming hinge knuckles each of which has a plurality of pintle receiving apertures located at different heights, a pilot having upwardly projecting elements forming cooperating hinge knuckles, and removable pintles for connecting said knuckles.

10. In a railroad vehicle, an underframe including a pilot beam having forwardly projecting elements forming hinge knuckles each of which has a plurality of pintle receiving apertures located at different heights, a pilot having upwardly projecting elements forming cooperating hinge knuckles, and removable pintles for connecting said knuckles, and a bracket for bracing said pilot from said beam, and means for securing said bracket at different heights on said pilot.

In testimony whereof I hereunto affix my signature this 21st day of May, 1923.

H. M. PFLAGER.
